UNITED STATES PATENT OFFICE.

ROBERT G. GRISWOLD, OF WESTFIELD, NEW JERSEY, ASSIGNOR TO DOHERTY RESEARCH COMPANY, OF NEW YORK, N. Y., A CORPORATION OF DELAWARE.

GAS WATER HEATER.

Application filed December 4, 1925. Serial No 73,167.

The present invention relates to means for heating water contained in the ordinary hot water tank or stand-boiler commonly found in houses. The water in such tanks is ordinarily heated by passing the water through a coil adapted to be heated by the house heating furnace or kitchen range. When gas becomes available many householders would like to use it for water heating purposes but for the expense involved in installing the customary gas burning apparatus.

The present invention has for its objects to provide a gas burning apparatus for use in connection with stand-boilers that shall be relatively inexpensive as compared with the customary gas hot-water heaters; that shall be efficient and safe in operation, and that shall be capable of being readily installed without interfering with such heating devices as may have been previously provided.

The gas burning apparatus is so constructed that the burning gas will flow along an exposed portion of the outside cylindrical surface of the water tank whereby the water in the tank will be heated by transmittal of heat directly through the walls of the tank. The apparatus is in the nature of a jacket or shell adapted to be secured around the tank, the shell being provided with two upwardly extending flues which are in communication at their upper ends, the burning gas going up one flue and down the other. The various features of construction will more fully appear from the detailed description taken in connection with the accompanying drawings forming part of their specification.

Referring to the drawings wherein the preferred form of apparatus is shown, Fig. 1 is a view showing a stand-boiler or tank as encased by a shell within which is a pair of flues through which the burning gases pass, part of the shell being broken away to show its construction;

Fig. 2 is a view in elevation looking at the assembly from the left in Fig. 1, the dotted lines indicating the flue passages and the arrows the direction of travel of the flue gases; and

Fig. 3 is a transverse section through the assembly, the view being taken on lines 3—3 of Fig. 1 and illustrating constructional features of the shell.

In the drawings, a stand-boiler 10 is shown as supported on a suitable stand 12 and as

provided with a cold water supply pipe 14 and a hot water outlet 16, both arranged as usual.

The water in the boiler is adapted to be heated by the burning of a small jet of gas issuing from the Bunsen burner 18 or similar simple type burner fed with gas through a pipe 20. The burning gases and products of combustion flow along a fixed path on the outside surface of the boiler, said path preferably taking the form of two upright flues or channels 22 and 24 separated by a partition 26 except at their upper ends which are in open communication as indicated at 28. Products of combustion leave the flue 24 by way of a suitable draft pipe 30 leading from the lower end of said flue.

The channels 22 and 24 are formed in a body which preferably, though not necessarily, is made from heat insulating sheet material, such as corrugated paper 32 and which is preferably formed as a jacket or shell to encase the boiler as shown, the body when made as a boiler enclosing jacket being preferably separable into two parts on the boiler diameter. That portion of the body in which the flues 22 and 24 are formed is made fire-proof in any suitable manner but preferably by first providing a layer of asbestos 34 and a layer of adamant cement 36 next to that. The partition 26 may be of any suitable material but is preferably made of a mixture of asbestos and cement. By forming the flue lining and partition of plastic materials, the flue and partition may be readily formed and moulded in one operation thereby reducing the cost of manufacture.

The top of the boiler is preferably covered over by the jacket primarily to prevent radiation of heat therefrom and secondarily to enable the jacket to be readily held in place on the boiler. However, the jacket may rest at its lower end on the rim 38 of the boiler supporting stand 12 as shown.

It will be clear from the foregoing and from the drawing that the jacket of corrugated material 32 covers and contacts with substantially the entire top and vertical surface of the stand boiler or tank 10 and that the jacket has a salient or outwardly projecting portion which is spaced from a portion of the boiler or tank along a vertical line to provide spaces for the flues, the area of the salient portion of the jacket being a minor

fraction only of the vertical area of the boiler or tank.

From the foregoing description it will be appreciated that the present invention provides a simple, practical and inexpensive apparatus for enabling a water boiler to be heated with gas. The body in which the flues are formed is readily secured to the stand boiler and when the body is made of corrugated paper and is made in the form of a jacket which encloses the boiler the radiation losses from the boiler will obviously be negligible and hence a very small amount of gas will be sufficient to heat the water within the boiler to the desired temperature.

Tests on the apparatus described above have shown that comparatively high combustion efficiencies may be obtained with this apparatus. The apparatus is designed more particularly to use a steady burning gas flame to maintain a body of water in the tank at substantially the desired temperature at all times. When operating the apparatus in this way only a comparatively small amount of gas need be burned in the burner 18 to maintain the water in the heater at the desired temperature, and at the same time the exhaust gases passing out of the outlet 30 will be substantially at atmospheric temperature. Furthermore, inasmuch as a relatively small amount of gas is burned, the products of combustion may be exhausted directly into the room in which the apparatus is placed, if so desired, instead of being exhausted into the outside air.

While the apparatus is preferably constructed in the manner shown in the drawings, it is obvious that certain changes may be resorted to without departing from the spirit of the invention. Reference is therefore made to the appended claims for a definition of the scope of the invention.

I claim:

1. An article of manufacture comprising a heat-insulating jacket of fibrous material, a longitudinally extending salient portion formed in one side of the jacket and grooved along its inner face, a partition dividing said portion for the major part of its length into two channels which are in communication at one of their ends, the channels and partition being constructed of fire-resistant material.

2. The combination with a water tank set with its longitudinal axis in the vertical position of an external heat insulating jacket for said tank, said jacket covering and contacting with substantially the entire top and vertical surface of said tank but being spaced from a portion of said tank along a vertical line, the area over which said jacket is spaced from said tank being a small fraction only of the vertical area of the tank, said space between the jacket and tank being closed at the top, vertical means dividing the space between said jacket and tank into flues connected at their tops and open at their bottoms, and a gas burner set to discharge upwardly into one of said flues.

In testimony whereof I affix my signature.

ROBERT G. GRISWOLD.
